CLAIM

The ornamental design for a boiling pot, as shown and described.

DESCRIPTION

FIG. 1 is a front, left and bottom perspective view of a boiling pot, showing my new design;

FIG. 2 is a rear, right and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a partially enlarged view thereof, taken from FIG. 2.

The broken lines shown in the drawings illustrate portions of the boiling pot that form no part of the claimed design.

(Continued)

The dot-dash broken lines of FIGS. 2 and 9 are included to show the partially enlarged views only and form no part of the claimed design.

1 Claim, 9 Drawing Sheets
